UNITED STATES PATENT OFFICE.

WILLIAM HARRY BARTELS AND CHARLES W. BARTELS, OF OAKLAND, CALIFORNIA.

POCKET-CONTAINER.

1,124,257.

Specification of Letters Patent. Patented Jan. 12, 1915.

Application filed February 13, 1914. Serial No. 819,454.

To all whom it may concern:

Be it known that we, WILLIAM HARRY BARTELS and CHARLES W. BARTELS, citizens of the United States, residing at Oakland, in the county of Alameda and State of California, have invented certain new and useful Improvements in Pocket-Containers, of which the following is a specification.

This invention relates to pocket containers and more particularly to a device for holding tobacco and cigarette papers.

The principal object of our invention is to provide a neat and compact container, which contains both the paper and tobacco and will conveniently fit the pocket.

Another object is to provide means for opening the container with the hand which holds it, that the tobacco may be conveniently poured into a paper preparatory to rolling a cigarette, and after pouring, the lid will automatically close thus preventing the contents from spilling. As the lids and all parts are tight fitting the contacts will be preserved in better condition than in the ordinary container.

With these and other objects in view our invention consists in the novel construction and arrangement of parts as herein illustrated and pointed out in the annexed claim.

Reference should be had to the drawing forming a part of this specification wherein,

Figure 1 is a view in perspective of our improved container showing the lid of the paper containing compartment partly open.

Fig. 2 is an enlarged sectional view on the line 2—2 Fig. 1. Fig. 3 is a transverse view in section through the upper part of the container. Fig. 4 is a view in section on the line 4—4 Fig. 1. Fig. 5 is a detailed sectional view in section on the line 5—5 Fig. 2.

Fig. 6 is an enlarged view in perspective of the hinged operating mechanism. Fig. 7 is a view in plan of the parts shown in Fig. 6, the same being slightly separated.

Referring to the corresponding parts by the same numerals of reference, 1 denotes an oval shaped body portion having frictionally engaged lids 2 and 3. The former is a plain lid and is provided for the purpose of filling the can. In the side of the body 1, we provide a pocket 3' closed by hinge lid 4 having a catch 4'. This pocket is of sufficient depth and size to accommodate the usual package of cigarette papers.

The lid 3 is provided with an opening 5 through which the contents are poured into

the cigarette papers and this opening is closed by a flap 6 pivoted to the inside of the lid as at 7 and having an angular rearward projection 8, on the sides of which are recessed notches 9. In contact with the back 60 8 is a rearwardly extending strip 11 and having coacting notches 10 with laterally projecting lugs 10' to engage the front of the projection 8. The other end of strip 11 65 is provided with a thumb contact 12, extending through a slotted opening 13 in the flange of the lid and upper edge of the body portion 1. This strip 11 is mounted in a compartment 14 formed in the upper end of 70 the body by a division wall 15 and within this compartment is a spiral spring 16 having its ends connected respectively to the rear of 8 and the thumb contact 12.

It will be evident that by pressing on the 75 thumb piece 12 strip 11 will push forward the part 8 and raise the flap as shown in dotted lines on Fig. 2. During this movement the part 8 moves a greater distance than the thumb piece hence the spring 16 80 will be placed in tension and as soon as the thumb piece is released will drop the flap into its closed position. The upper edge of the body portion acts as a stop to prevent the flap from closing too far into the can. 85

It will thus be seen that we have provided a container, which may be conveniently operated by one hand leaving the other hand free to hold the paper, which is self closing and which fits the pocket. 90

With our device it is very easy to secure a required amount of material for a cigarette, consequently avoiding the waste which often takes place when using the ordinary tobacco container. 95

While we have shown the preferred embodiment of our invention it will of course be understood that changes may be made in minor details and form of construction, these also we wish to cover as broadly as possible. 100

What we claim as new and wish to cover by Letters Patent is:—

In a pocket container of the character described comprising the combination of an 105 oval body, a frictionally engaged lid closing one end of said body portion, an opening in one side of said lid, a hinged closure for said opening, a rearward extension for said closure, notches in the sides thereof, a rearward extending strip engaging the back of 110 said extension arms on the sides thereof

52
entering the notches of said extension, laterally extending lugs on said arms engaging the front of said extension, a button on the other end of said strip, said button extending through an opening in the other side of said lid so that pressure thereon will raise said lid, and spring means for returning said lid to its normally closed position.

In testimony whereof we affix our signatures in presence of two witnesses.

WILLIAM HARRY BARTELS.
CHAS. W. BARTELS.
